UNITED STATES PATENT OFFICE.

JAMES ALLEN HASKETT, OF PARSONS, KANSAS.

DESIGN FOR A BUTTON-HOOK.

SPECIFICATION forming part of Design No. 27,252, dated June 29, 1897.

Application filed April 24, 1897. Serial No. 633,805. Term of patent 14 years.

To all whom it may concern:

Be it known that I, JAMES ALLEN HASKETT, a citizen of the United States, residing at Parsons, in the county of Labette and State of Kansas, have invented and produced a certain new and original Design for Button-Hooks; and I do declare the following to be a full, clear, and exact description of the invention, such as will enable others skilled in the art to which it appertains to make and use the same.

My invention has relation to a new and ornamental design for a button-hook; and it consists of a button-hook of the configuration and ornamentation shown in the accompanying drawing, in which I have illustrated my invention in perspective.

The leading features of my design consist in a button-hook provided with a hook 1, shank 2, and kite-shaped handle 3, formed 20 with a heart-shaped aperture 4, above which the body of the handle may be suitably ornamented or upon which a suitable advertisement may be placed.

Having thus described my design, what I 25 claim as new and original, and desire to secure by Letters Patent of the United States, is—

The design for a button-hook, as herein shown and described. 30

In testimony whereof I hereunto affix my signature in presence of two witnesses.

JAMES ALLEN HASKETT.
